CLAIM

The ornamental design for a contact lens antenna, as shown and described.

DESCRIPTION

FIG. 1 is a perspective view of the contact lens antenna of the present design;

FIG. 2 is a top side view thereof;

FIG. 3 is a bottom side view thereof;

FIG. 4 is a left side view thereof;

FIG. 5 is a right side view thereof;

FIG. 6 is a front view thereof;

FIG. 7 is a rear view thereof; and,

FIG. 8 is a perspective view showing the contact lens antenna positioned on an eye.

The dash-dot-dash lines showing an eye in FIG. 8 represent environmental subject matter, and even broken lines are included for the purpose of illustrating portions of the contact lens antenna that form no part of the claimed design.
